FLETCHER AMES, OF PALO ALTO, CALIFORNIA, ASSIGNOR TO AMES HARRIS NEVILLE CO., OF SAN FRANCISCO, CALIFORNIA, A CORPORATION OF CALIFORNIA

TENT SUPPORT

Application filed October 15, 1930. Serial No. 488,800.

This invention relates to a tent support and especially to a portable support which may be folded to form a compact bundle for shipment, storage, or otherwise.

The object of the present invention is to generally improve and simplify the construction and operation of tent supports; to provide a tent support which is portable and foldable so as to form a compact bundle for shipment, storage, or otherwise; to provide a tent support which may be quickly and readily set up or taken down; and, further, to provide a tent support from which the tent is suspended and held in a taut condition and in which guy ropes, pegs, and other fastening and bracing means may be entirely eliminated.

The tent support is shown by way of illustration in the accompanying drawings, in which—

Fig. 1 is a perspective view of the tent supporting frame looking from the rear of the tent,

Fig. 2 is a similar view of the tent supporting frame looking from the front of the tent,

Fig. 3 is a central, vertical, longitudinal section of the tent and the frame supporting the same.

Referring to the drawings in detail, A indicates the roof section of a tent, 2 the side walls of the tent, and 3 the end wall. The tent shown in the present instance is particularly intended for practicing golf. That is, the golf ball is placed on a tee some distance in front of the tent and the person practicing drives the ball into the tent and for this reason no front flap or closure is disclosed. The tent shown may otherwise be referred to as a lean-to type of tent and if that type is used a front section may be employed.

Where the tent is used in golf practice a plurality of intermediate strips, such as shown at 4, are employed. These are hung from the roof of the tent in any suitable manner some distance in front of the rear wall section 3. By being so positioned the force of the golf ball is broken and the impact action against the rear wall 3 is materially reduced. A bottom flap 5 is secured to the rear

wall and this extends forwardly and beneath the strips 4, thus returning the balls to the front end of the tent where the player may readily gather them.

The frame whereby the tent is supported forms the main subject matter of the present application. It consists of pairs of legs such as indicated at 6 and 7. One pair is placed on each side of the tent and they are connected by cross poles such as shown at 8 and 9. The legs 6 and 7 of each pair are pivotally connected as at 7a so that they may be folded to lie parallel when the tent is not in use and also to permit the formation of a compact bundle for shipment, storage, or the like. When the tent is to be erected cross bar 8 is slipped through a loop or enlarged hem portion 10 formed at the front end of the roof section. The supporting legs 6 are provided with pegs 11 and these are passed through the perforated ends of the pole. The legs are then extended as shown in either Fig. 1 or 2 and the rear cross pole 9 is applied in the same manner. That is, its ends are drilled or perforated to receive the supporting pegs 11a. The rear end of the roof section is provided with an extended flap 12 and this is provided with eyelets. A rope or like fastening means 13 is laced through the eyelets and passed around the cross pole 9 and the tent roof may thus be stretched tight between the cross poles. The supporting frame is then braced by angle braces 14 and horizontal braces 15, these braces materially increasing rigidity of the supporting frame as a whole. The braces 14 and 15 employed are identical in construction. For instance, the braces 15 are pivotally secured as at 16 to the legs 7 of each pair. The opposite end of each brace 15 has a hole drilled therein and so have the supporting legs 6. These holes are brought into register and a bolt with an ordinary wing nut 17 is applied, thus securing the horizontal braces in place and thereby securing the legs 6 and 7 rigidly against pivotal movement.

The angle braces which brace the frame laterally are similarly constructed, their lower ends being pivotally attached as at 18 to the upper ends of the legs 7 while the oppo-

site ends of the braces are drilled and so is the cross pole 9. The holes are brought into register and bolts are passed through which are secured by wing nuts 19. The supporting frame thus erected maintains the roof section of the tent stretched in an elevated position with the side walls and the end wall of the tent suspended therefrom, in this manner eliminating the use of guy ropes, fastening pegs, or braces of any character. The entire tent, being so to say, suspended from the cross poles of the supporting frame.

The frame, together with the tent supported thereby, may be quickly and readily set up or taken down and when taken down it is possible to swing the supporting legs of each pair into a parallel position and to place the cross poles parallel thereto. The tent may then be wound about the poles and a compact small bundle is formed which can be readily stored or shipped as the case may be.

While the frame has been described as a support for a golf practicing tent, it is obvious that a lean-to or similar type of tent may be employed, and while certain features of the present invention are more or less specifically described, I wish it understood that various changes may be resorted to within the scope of the appended claims. Similarly, that the materials and finishes of the several parts employed may be such as the manufacturer may decide, or varying conditions or uses may demand.

Having thus described my invention, what I claim and desire to secure by Letters Patent is—

1. The combination with a tent having a flat roof section and an end and side wall sections attached thereto, of a supporting frame for the tent, said frame comprising pairs of pivotally connected leg members normally crossing each other when extended to support the tent, there being one pair of supporting legs disposed on each side of the tent and exterior thereof, a pair of cross poles supported by the upper ends of the leg members, and means securing the front and rear ends of the tent roof section with relation to said cross poles so as to maintain the roof of the tent in an elevated position with the end and side wall sections of the tent suspended therefrom.

2. The combination with a tent having a flat roof section and an end and side wall sections attached thereto, of a supporting frame for the tent, said frame comprising pairs of pivotally connected leg members normally crossing each other when extended to support the tent, there being one pair of supporting legs disposed on each side of the tent, a pair of cross poles perforated at their ends, pegs on the upper ends of the supporting legs adapted to extend through the perforated ends of the poles to support the same, means securing the front end of the tent roof to one pole, adjustable means securing the rear end

of the tent roof to the other cross pole, said adjustable means permitting stretching of the tent roof to maintain it in a taut elevated position with the end and side wall sections of the tent freely suspended therefrom.

3. The combination with a tent having a flat roof section and an end and side wall sections attached thereto, of a supporting frame for the tent, said frame comprising pairs of pivotally connected leg members normally crossing each other when extended to support the tent, there being one pair of supporting legs disposed on each side of the tent, a pair of cross poles perforated at their ends, pegs on the upper ends of the supporting legs adapted to extend through the perforated ends of the poles to support the same, means securing the front end of the tent roof to one pole, adjustable means securing the rear end of the tent roof to the other cross pole, said adjustable means permitting stretching of the tent roof to maintain it in a taut elevated position with the end and side wall sections of the tent suspended therefrom, and means for bracing the cross poles with relation to the supporting legs to insure lateral rigidity.

4. The combination with a tent having a flat roof section and an end and side wall sections attached thereto, of a supporting frame for the tent, said frame comprising pairs of pivotally connected leg members normally crossing each other when extended to support the tent, there being one pair of supporting legs disposed on each side of the tent, a pair of cross poles perforated at their ends, pegs on the upper ends of the supporting legs adapted to extend through the perforated ends of the poles to support the same, means securing the front end of the tent roof to one pole, adjustable means securing the rear end of the tent roof to the other cross pole, said adjustable means permitting stretching of the tent roof to maintain it in a taut elevated position with the end and side wall sections of the tent suspended therefrom, and other brace members connecting the pivotally connected supporting legs and securing them in extended crossed position.

5. In a structure of the character described, a frame comprising a pair of pivotally connected supporting leg members normally crossing each other, a second pair of pivotally connected leg members normally crossing each other and spaced from the first named legs, a pair of cross poles connecting the upper ends of each pair of pivotally connected supporting leg members, a sheet of fabric stretched between the cross poles and secured thereto, said fabric forming the roof of a tent, and a pair of tent side walls and an end wall secured to the roof and freely suspended therefrom, said side walls of the tent being disposed between the pairs of pivotally connected supporting legs.
